UNITED STATES PATENT OFFICE

WEBSTER E. JANSSEN, OF NEW YORK, N. Y.

PLAYER-PIANO CASE

Application filed October 11, 1928. Serial No. 311,753.

My invention relates to player-piano cases for enclosing the usual player-piano action and keys, and more particularly for such piano cases embodying the customary equipment and attachments for a writing desk or secretary, into which the player-piano case may be converted at will.

The objects of my invention are, among other things, to provide a new and improved player-piano case of this combined type for an upright piano in which the various parts usually embodied in a player-piano as well as in a collapsible writing desk are conveniently and compactly arranged within the customary outline or contour of the writing desk so that this improved player-piano case may be readily transformed from a writing desk to a piano case in open position for manual or note-sheet playing, and vice versa, with a minimum movement and coaction of parts in the two devices which are disposed so as not likely to get out of position.

A further feature is to provide an improved arrangement for the tracker-box and tubes located in the desk-top and leading to the player action proper carried in the lower part of the case, so that the upper part of the case or desk-top may be swung backwardly and held safely in disassembled position without in any way disturbing the proper register of the tubes connected with the row of holes in the tracker-bar when restored in operative position.

Such arrangement will permit of ready access to the various parts of the player-action with a minimum movement of the parts to enable tuning of the piano and other repairs to be made without in any way altering or disturbing the delicate arrangement of the tube system connected to the tracker, or disarranging the component parts of the secretary or writing-desk as a whole.

Further objects and advantages of my improved player-piano case will be hereinafter

set forth, and the drawings show a preferred embodiment of my invention in which—

Fig. 1 is a front elevation of my player-piano case with the music rack in position;

Fig. 2 is a rear elevation partly broken away in section;

Fig. 3 is a side view with the upper part of the case swung backward to a horizontal position;

Fig. 4 is a side sectional view showing the inner arrangements of the piano case and writing-desk;

Fig. 5 is a detail sectional view of the tube junction-block connections for the player action with the tracker-bar; and

Fig. 6 is a perspective view of the rear of the piano case showing the tube system in disconnected position.

Similar numerals refer to similar parts throughout the several figures.

Referring to the drawings, the lower part of the player-piano case which embodies the player action and writing-desk parts comprises the side-pieces 7 mounted on the bottom 8 supported by the feet 9 which rest on the floor. Two sets of side-drawers 10 are arranged adjacent the side-pieces 7 between which is the key-board 11 extending above the side-drawers 12. The rear panel 12 is arranged back of the drawers 10 and midway between the bottom 8 and key-board 11 (Fig. 4).

The player-action proper is arranged back of the panel 12 and comprises the pumping-bellows 13 operated in the usual manner to provide exhaust pressure. In Fig. 4 I have shown the electric motor 14 mounted on the bottom 8 to actuate the movable leaf 15 of the bellows 13 which is connected by the pipe 16 to the wind-chest 17. This wind-chest is connected in the usual manner to the series of action pneumatics 18 arranged on the cross-bracket 19, the action pneumatics 18 actuating the hammers 20 (only one being shown in Fig. 4) which strike the strings 21.

carried by the back plate 22 adjacent the sounding-board 23 and back 24 of the piano case proper.

Connected to the series of action pneumatics 18 are the series of rubber tubes 25 which are brought together and pass through the large opening 26 (Figs. 2 and 3) cut preferably in a corner of the back 24. The upper ends of the tubes 25 are attached to nipples 26^a arranged in suitable holes 27 drilled through the removable junction-block 28.

The bottom 29 of the top piece 30 of the writing-desk extends across the lower part of the piano case, and rests on the side-pieces 7 and back 24 (Fig. 4). Below the rear end of the bottom 29 is the cross-piece 31 to which the bottom 29 is fastened by hinges 32 so that the desk-top 30 may be swung backwardly from its Fig. 2 to the Fig. 3 horizontal position to be supported by the leg 33 hinged at 34 to the rear top portion of the desk-top 30. The leg 33 resting on the floor will hold the desk-top 30 in approximately horizontal position (Fig. 3), thereby exposing the player-action proper arranged in the lower part of the piano case as hereinbefore described.

Within the lower portion of the desk-top 30 is the tracker-box 35 having the usual tracker-bar 35^a and upper music roll 36 and take-up roll 37 driven in the usual manner from the electric motor 38 (Figs. 2 and 4). The customary wind-motor for driving the rolls 36 and 37 may be used instead of the electric motor 38. The note-sheet 39 registers with the row of holes 40 cut in the tracker-bar 35^a, and a series of short tubes 41 connect the tracker-holes 40 with the nipples 42 fastened in holes 43 drilled in the vertical junction-block 44 (Fig. 5) mounted in the rear of the desk-top 30.

The removable junction-block 28 is fastened snugly to the face of the junction-block 44 in a surface-to-surface contact by the screws 45 so that each of the tubes 25 registers with its corresponding tube 41 (Fig. 5) whereby each of the tracker-holes 40 is properly connected to its respective action pneumatic 18 when the parts are in the position shown in Figs. 2 and 4. The junction-blocks 28 and 44 carry the perforated facings 46 and 47 respectively, preferably made of buck-skin to prevent any leakage when the two junction-blocks are fastened together as shown in Fig. 5. The desk-top 30 is provided with two sets of folding hinged doors 48 and 49 which may be folded back to expose the front of the desk-top 30 when required.

The key-slip 50 extends horizontally below the front edges of the piano keys 51, and is fastened to the key-board 11 in the usual manner. The piano keys 51 are connected by the abstracts 52 to the hammers 20 by the usual mechanism, all as shown in Fig. 4. The cross-bar 53 extends between the side-pieces 7 to 65 which is hinged the upper foldable cover 54.

The lower cover 55 is hinged to the cover 54, and is foldable back thereon to form the music-rack with the music slip 56 attached to the lower exposed portion of the lower cover 55 (Fig. 4). Hinged to the back of the cover 54 is the pivoted two-arm bracket 57 to support the music-rack.

Referring more particularly to Fig. 4, the writing-desk compartment comprising the pigeon-holes 58 is preferably formed as a unit and is attached to the side-pieces 7 by brackets 59 secured by the screws 60. This unit may be readily removed from the player-piano case when any repairs or adjustment of the player action becomes necessary.

Between the side-pieces 7 is the cross-bar 61 extending above the piano keys 51 and the inner end 62 of the desk-top 30 slidably rests on the bar 61. The front edge of this inner end 62 is provided with a hinge 63 to which is fastened the outer desk top 64 which, when swung to a horizontally aligned position with the inner end 62, forms a continuous flat surface for the writing-desk. Fastened at right angles to the outer desk-top 64 is the curved brace-member 65 having handle buttons 66 to bear on coating buttons 67 projecting from the key-slip 50 (Fig. 4) to aid in holding the outer desk top 64 firmly in writing position. When the two desk top members 62 and 64 are folded back as shown in Fig. 4, they are adapted to be moved rearwardly into the piano case beneath the writing desk compartment with the brace member 65 forming a cover for the pigeon-holes 58 and the piano keys 51 are exposed for manual playing, if desired, as shown in Figs. 1 and 4.

The operation of my improved player-piano case construction is apparent from the drawings. Figs. 1 and 4 show the position of the piano case and writing-desk when the case is open and in readiness either for use with the note-sheet 39 operating the player action or for manual playing by the keys 51. The two-piece foldable cover portions 54 and 55 are folded together to form the music-rack, and the writing desk top members 62 and 64 are folded in mutual parallelism and retracted as shown in Fig. 4.

When it is desired to tune the piano or make any repairs to the player action arranged in the lower part of the case, the junction-blocks 28 and 44 may or may not be disconnected by unscrewing the screws 45 (Fig. 6), and the entire desk-top 30 is then swung backwardly on the hinges 32 with the leg 33 forming an upright support (Fig. 3). When the desk-top 30 is brought back to vertical position, the player action is easily restored to operative connection with the note-sheet 39 and tracker-bar 35 mechanism by joining the junction-blocks 28 and 44 as shown in Fig. 5.

The advantages of my improved player-

piano case will be readily appreciated in providing a compact and easily convertible case and writing desk which will occupy a minimum space or area within the room of a house or apartment, coupled with a player action and note-sheet-tracker mechanism housed in separable parts of the case as a whole, whereby the upper desk-top containing the tracker mechanism and connecting tubes may be bodily swung back and held to enable the tuner to have ready access to the tuning-pins without disturbing the proper register of the system of tubing connecting the series of player action pneumatics with the tracker-bar. Other devices may be substituted for the tracker mechanism in the upper desk top without departing from my invention, and furthermore an organ or like musical instrument playing action may be used instead of a player-piano action shown as a preferred embodiment, all with the same advantages and economies which I have hereinbefore described.

I claim as my invention:

1. A player-piano case comprising a lower portion containing the player action, an upper portion pivoted to said lower portion to swing backwardly and containing the note-sheet-tracker mechanism, and operative connections between the player action and tracker mechanism permitting said upper portion to be swung backwardly without disturbing said operative connections.

2. A player-piano case comprising a lower portion containing manually-operated keys, a writing desk top foldable and slideable within the case and a player action, and an upper desk top pivoted to said lower portion to swing backwardly to expose the top of the player action in said lower portion.

3. A player-piano case comprising a lower portion containing manually-operated keys, a writing desk top foldable and slideable within the case and a player action, and an upper desk top pivoted to said lower portion along its rear top edge to swing backwardly to expose the top of the player action in said lower portion.

4. A player-piano case comprising a lower portion containing manually-operated keys, a writing desk top foldable and slideable within the case and a player action, an upper desk top pivoted to said lower portion to swing backwardly to expose the top of the player action in said lower portion, and means for supporting said upper desk top when swung backwardly in substantially horizontal position.

5. A player-piano case comprising a lower portion containing the player action, an upper portion pivoted to said lower portion and containing the note-sheet-tracker mechanism, and separable tubing systems connecting the player action and tracker mechanism to per-

mit said upper portion to be swung backwardly to expose said player action.

6. A player-piano case comprising a lower portion containing the player action, an upper portion pivoted to said lower portion to and containing the note-sheet-tracker mechanism, separable tubing systems connecting the player action and tracker mechanism to permit said upper portion to be swung backwardly to expose said player action, and means for supporting said upper desk top when swung backwardly in substantially horizontal position.

7. A player-piano case comprising a lower portion containing the player action, an upper portion pivoted thereto and containing the note-sheet-tracker mechanism, and a tubing system comprising separable junction-blocks to maintain collective registration of the individual tubes for the player action and tracker mechanism.

8. A player-piano case comprising a lower portion containing the player action, an upper portion pivoted thereto along its rear top edge and containing the note-sheet-tracker mechanism, and a tubing system comprising separable junction-blocks to maintain collective registration of the individual tubes for the player action and tracker mechanism.

9. A player-piano case comprising a lower portion containing the player action, an upper portion pivoted thereto along its rear top edge and containing the note-sheet-tracker mechanism, and a tubing system comprising separable junction-blocks to maintain the collective position of the individual tubes when said junction-blocks are detached from each other.

10. A player-piano case comprising a lower portion containing the player action, an upper portion pivoted thereto along its rear top edge and containing the note-sheet-tracker mechanism, and a tubing system comprising separable junction-blocks to maintain the collective position of the individual tubes for the player action and tracker mechanism when the junction-blocks are detached from each other, and a leg hinged to said upper portion to support same in substantially horizontal position.

11. In a player-piano case, a lower portion containing the player action, an upper desk top pivoted thereto to swing backwardly to horizontal position and expose said player action, a note-sheet-tracker mechanism in said upper desk top, a plurality of tubes leading from the tracker to a junction-block, a detachable junction-block in register with said first junction-block, a like plurality of tubes leading from the detachable junction-block to the player action, and means for holding said junction-blocks in registering position.

12. In a player-piano case, a lower portion containing the player action, an upper

desk top pivoted thereto to swing backwardly to horizontal position and expose said player action, a note-sheet-tracker mechanism in said upper desk top, means for supporting said upper desk top in horizontal position, a plurality of tubes leading from the tracker to a junction-block, a detachable junction-block in register with said first junction-block, a like plurality of tubes leading from the detachable junction-block to the player action, and means for holding said junction-blocks in registering position.
